(57) **CLAIM**

The ornamental design for a ruggedized side connector for
audio accessories, as shown and described.

DESCRIPTION

FIG. 1 is a top, left perspective view of a ruggedized side
connector for audio accessories, showing my new design;
FIG. 2 is a rear, right perspective view thereof, showing pins
to connect with audio accessories;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings represent portions of the
ruggedized side connector that form no part of the claimed
design. The break lines within the broken line environment
also form no part of the claimed design.
